[57] **CLAIM**

The ornamental design for a holder for flexible sheet material, as shown and described.

DESCRIPTION

FIG. 1 is a top perspective view of a holder for flexible sheet material showing my new design;

FIG. 2 is a top plan view on an enlarged scale;

FIG. 3 is a side elevational view of FIG. 2, the opposite side being a mirror image thereof;

FIG. 4 is an end elevational view of FIG. 2, the opposite end being a mirror image thereof;

FIG. 5 is a bottom plan view of FIG. 2; and

FIG. 6 is a top perspective view of FIG. 1, the paper sheet depicted by means of broken lines being shown for illustrative purposes only and forming no part of the claimed design.

FIG. - 1

FIG. - 2

FIG. -3

FIG. -4

FIG. -5
